COMBINATION LOOSE LEAF NOTEBOOK,
PAPER CONTAINER, AND ACCESSORY KIT

Jacob Boelema, Jr., Grand Rapids, Mich.

Application March 20, 1942, Serial No. 435,458

7 Claims. (Cl. 281—31)

The present invention relates to loose leaf notebooks, and more particularly to a combined loose leaf notebook, paper container, and accessory kit.

The primary objects of the invention are to provide a loose leaf notebook which, while possessing all of its customary usefulness as a loose leaf notebook, combines in addition storage space for ordinary unperforated typewriter paper or the like and a kit for accessories such as pencils, pens, paint brushes, ruler, compass, erasers, etc., which articles are commonly, inconveniently, and often clumsily carried by students in separate containers; to provide such a structure in which lids normally seal the paper storage space and the accessory kit so that the contents thereof may not inadvertently be spilled; to provide such a structure which may be made of suitable material such as sheet metal at relatively small expense and consequent low cost to the purchaser; to provide such a structure which combines a maximum of storage space with a minimum of bulk; and in general to provide such a loose leaf notebook or binder which is rugged and sturdy in construction, convenient in use, and attractive in appearance.

Illustrative embodiments of the invention are shown in the accompanying drawings wherein:

Figure 1 is a perspective view of my new combined loose leaf notebook, paper container, and accessory kit in closed position for carrying;

Figure 2 is a perspective view of the same in an open position for use;

Figure 3 is an enlarged sectional view of the same taken on line 3—3 of Figure 1;

Figure 4 is a plan view of certain parts thereof shown disassembled to better illustrate the relationship between these parts;

Figure 5 is a perspective view similar to Figure 2 of a modified form of the invention, a portion thereof being broken away;

Figure 6 is a plan view of a further modified form of binder cover for the structure; and

Figure 7 is an enlarged sectional view thereof taken on line 7—7 of Figure 6.

Referring now in detail to these drawings wherein like parts are designated by the same numerals in the several views, and referring first particularly to Figures 1 to 4 inclusive, the loose leaf binder there shown comprises a center binder back 1 in the form of a flat strip which may conveniently be made of sheet metal, and upon which is mounted a conventional loose leaf binding device generally designated 2 and consisting of a sheet metal base 3 secured to the binder back 1

by means of rivets 4, and a pair of interconnected split wire rings 5 springably operable to open and closed positions and adapted to hold loose leaf paper sheets 6 having perforations 7. The paper sheets 6 have flanges 8 and 9 on its opposite edges respectively, which pairs of flanges are curled to form aligned hinge eyes.

A pair of binder covers generally designated 10, 11 may also conveniently be made of sheet metal and are shallow box-shaped in formation, being of generally rectangular shape with laterally extending peripheral rims or edges 12, 13 respectively. The inner edges of said box-shaped binder covers 10, 11 are provided with a plurality of spaced flanges 14, 15 respectively, here shown as five in number on each binder cover 10, 11, the flanges on each binder cover being curled to form aligned hinge eyes. The opposite outer rims or edges 12, 13 of the box-shaped binder covers 10, 11 have their middle portions stamped outwardly to form keepers 16, 17 respectively whose functions are hereinafter described.

A pair of flat box lids 18, 19 may likewise conveniently be made of sheet metal, and these box lids 18, 19 have pairs of flanges 20, 20 and 21, 21 respectively, on their inner edges, which pairs of flanges are also curled to form aligned hinge eyes. The opposite outer edges of the box lids 18, 19 have centrally disposed flanges thereon which are curled as best seen in Figure 3 to form spring latches 22, 23 respectively adapted to engage the keepers 16, 17 on the box-shaped binder covers 10, 11. The box lids 18, 19 are further provided with pairs of voids 24, 24 and 25, 25 respectively, in registry with the rings 5 of the binding device 2, for a purpose herein-after described.

The binder back 1, the binder covers 10 and 11, and the box lids 18 and 19, are all held in hingedly connected assembly by means of hinge pins 26, 27. The pin 26 passes through the aligned hinge eyes, 8 on the binder back 1, 14 on the binder cover 10, and 20 on the box lid 22; and the pin 27 passes through the aligned hinge eyes, 9 on the binder back 1, 15 on the binder cover 11, and 21 on the box lid 23. The hinge pins 26, 27 are riveted at their outer ends to permanently secure these parts in assembly.

As seen in Figures 2 and 3 of the drawings, the box-shaped binder cover 10 is conveniently used as a container or storage compartment for loose sheets of unperforated typewriter paper 28, carbon paper or the like, while the other box-shaped

binder cover 11 is conveniently used as an accessory kit for containing crayons 29, rules 30, protractor 31, eraser 32, or other miscellaneous articles. The modified form of the invention shown in Figure 5 is identical to that shown in Figures 1 to 4 inclusive and like reference numerals have been used throughout, except that the shallow box-shaped binder cover 11¹ in Figure 5 is provided with a partitioning member 33, which may be of any convenient form and of sheet metal secured in position as by means of welding. As shown, the partitioning member 33 is designed so as to provide a long space in the binder cover for the accommodation of the 12-inch ruler 30, and smaller compartments for containing pencils 34, crayons 29, a brush 35, pens 36, compass 37 and eraser 32, or other miscellaneous articles. The modified form of the invention illustrated in Figures 6 and 7 shows a shallow box-shaped binder cover 11² partitioned similarly to the binder cover 11¹ shown in Figure 5 except that in this instance the partitions 38 are stamped in the sheet metal binder cover 11².

It will readily be seen that inasmuch as the box lids 18 and 19 rest on the rims or edges 12, 13 of the binder covers 10, 11 respectively, those edges serve as firm supports for the loose leaf paper 6 secured in the binder device, when the notebook is opened for use. It will also be seen that the box lids 18, 19 may be firmly but detachably secured in sealing positions over the binder covers 10, 11 by means of the spring latches 22, 23 on the box lids which engage the keepers 16, 17 on the binder covers.

As best illustrated in Figure 5, the voids 24, 24 and 25, 25 in the box lids 18 and 19 respectively, which are in registry with the rings 5 on the binding device 2, permit the box lids to be rotated to open positions more than ninety degrees and past the binding rings 5 when the binder is open and the binder covers lie flat. Thus access may be had to the interior of either binder cover without the necessity of holding its box lid in open position.

While but several specific embodiments of the invention have been herein shown and described, it is to be understood that numerous details of construction of those particular embodiments may be altered or omitted without departing from the spirit of the invention as the same is defined by the following claims.

I claim:

1. In a structure of the class described, a sheet metal binder back having a loose leaf binding device mounted thereon and a flange on each opposite edge thereof curled to form a hinge eye, a pair of shallow box-shaped sheet metal binder covers each provided with a flange on one edge thereof curled to form a hinge eye and with an outwardly stamped keeper on the opposite edge thereof, a pair of sheet metal box lids each provided with a flange on one edge thereof curled to form a hinge eye and with a flange on the opposite edge thereof curled to form a spring latch, and a pair of hinge pins each passing through the hinge eye on one edge of the binder back, through

the hinge eye on one of said binder covers and through the hinge eye on one of said box lids, the latches on said box lids being adapted to springably engage the keepers on said binder covers respectively.

2. In a structure of the class described, a binder back having a binding device mounted thereon comprising a plurality of binding rings adapted to hold loose leaf sheets, a pair of shallow box-shaped binder covers hingedly connected to said binder back at opposite sides thereof, and a pair of box lids hingedly connected to the binder back at opposite sides thereof and to the adjacent binder covers respectively, said box lids each being provided with a plurality of voids in registry with the rings of the binding device so that when the binder is open and the binder covers lie flat, the box lids may be rotated more than ninety degrees and past the binding rings.

3. In a structure of the class described, a back frame, and a pair of containers open at their inner sides and each having a peripheral rim and a lid, the respective containers adjacent the free edges of their rims and their lids adjacent their inner edges being hingedly connected with the back frame and in laterally spaced parallel relation.

4. In a structure of the class described, a back frame, and a pair of containers open at their inner sides and each having a peripheral rim and a lid, the respective containers adjacent the free edges of their rims and their lids adjacent their inner edges being hingedly connected coaxially with the back frame and in laterally spaced parallel relation.

5. In a structure of the class described, a back frame, and a pair of containers open at their inner sides and each having a peripheral rim and a lid, the respective containers adjacent the free edges of their rims and their lids adjacent their inner edges being hingedly connected coaxially with the back frame and in laterally spaced parallel relation, so that in the flat fully open position of the structure the lids in their container-closing positions may lie supported planiform on their receptacles' rims.

6. In a structure of the class described, a back frame having a loose leaf binding device mounted on its inner side, and a pair of containers open at their inner sides and each having a peripheral rim and a lid, the respective containers adjacent the free edges of their rims and their lids adjacent their inner edges being hingedly connected with the back frame and in laterally spaced parallel relation.

7. In a structure of the class described, a back frame, and a pair of containers open at their inner sides and each having a peripheral rim and a lid, the respective containers adjacent the free edges of their rims and their lids adjacent their inner edges being hingedly connected with the back frame and in laterally spaced parallel relation, and the receptacles and their lids having latching means.

JACOB BOELEMA, JR.
